UNITED STATES PATENT OFFICE

SAMUEL MAKSIK, OF BROOKLYN, NEW YORK, ASSIGNOR TO MICHEL, MAKSIK & FELDMAN, INC., OF NEW YORK, N. Y., A CORPORATION OF NEW YORK

DESIGN FOR A HAND BAG

Application filed August 10, 1932. Serial No. 44,571. Term of patent 3½ years.

To all whom it may concern:

Be it known that I, SAMUEL MAKSIK, a citizen of the United States, residing at Brooklyn, in the county of Kings, State of New York, have invented a new, original, and ornamental Design for Hand Bag, of which the following is a specification, reference being had to the accompanying drawing, forming part thereof, in which:

Fig. 1 is a perspective view;

Fig. 2 is an end view of a hand bag; and

Fig. 3 is a cross-section on the line 3—3 of Fig. 1.

The characteristic feature of my design resides in the fact that the upper corners of the bag covering are cut-away so as to show the central frame member which is likewise covered with fabric.

I claim:

The ornamental design for a hand bag substantially as shown and described.

SAMUEL MAKSIK.
